UNITED STATES PATENT OFFICE.

PETER DRUGAS, OF CHICAGO, ILLINOIS.

BROOM FOR STREET-SWEEPING MACHINES.

1.295.136.

Specification of Letters Patent. Patented Feb. 25, 1919.

Application filed October 27, 1917. Serial No. 198,754.

To all whom it may concern:

Be it known that I, PETER DRUGAS, a subject of the King of Greece, and a resident of the city of Chicago, in the county of Cook and State of Illinois, have invented certain new and useful Improvements in Brooms for Street-Sweeping Machines; and I do hereby declare that the following is a full, clear, and exact description of the same, reference being had to the accompanying drawings, and to the numerals of reference marked thereon, which form a part of this specification.

15 Brooms for street sweeping machines as heretofore constructed have had the broom straws or ratan glued in place which is not only a tedious operation but an expensive one as well. Also much difficulty has been experienced in replacing worn-out straws
20 or ratan.

It is an object of this invention to provide a street sweeping machine broom in which the broom drum or mandrel is constructed of interfitting apertured sections, 25 each of which is provided with means to engage in the apertures to firmly bind the straws or ratan in place.

It is a further object of this invention to provide a device of the class specified in which repairs may be quickly made by the removal of one or more sections to permit the ready removal of old or worn fibers and the insertion of the proper number of new straw, ratan or broom fibers after which the sections may again be clamped together to firmly bind the fibers in place.

It is further an object of this invention to provide a device of the class specified in which transverse passages or apertures are provided in the sections thereof for the insertion of the proper number of broom fibers and in which said sections are provided with interfitting ribs and teeth adapted to engage in or partly fill the apertures to form a mechanical and positive binding element for firmly attaching the broom fibers in place.

The invention (in a preferred form) is illustrated in the drawings and hereinafter 50 more fully described.

On the drawings:

Figure 1 is a side view of a broom embodying my invention.

Fig. 2 is an end view thereof.

Fig. 3 is a transverse vertical section of 55 the broom.

Fig. 4 is an enlarged transverse section of one quarter of the broom drum or mandrel showing the sections associated together.

Fig. 5 is an enlarged top plan view of one of the outside sections forming each quarter of the broom drum. 60

Fig. 6 is an enlarged top plan view of the middle section.

Fig. 7 is an enlarged top plan view of the 65 other outside section.

Fig. 8 is an edge view of the middle section or the section shown in Fig. 6.

As shown on the drawings:

The reference numeral 1, indicates the complete broom assembled which is constructed of four primary drum sections which when bolted together form the drum in which the broom fiber is held. Each primary or main drum section in the present instance is constructed of three secondary auxiliary sections 2, 3 and 4, as shown in Figs. 5 to 7, inclusive. Each primary drum section is provided with rows of fiber receiving apertures or passages 5, 6, 7, 8, 9, 10 and 11.

As shown the section 2, is provided with a rib 12, and between the apertures 6, the section is cored out to provide passages 13, shown in dotted lines. Said passages 13, 85 communicate with the apertures 5, and are open through the inner side of the section. This section 2, is also cored out to provide a rectangular recess 14, also shown in dotted lines in Fig. 5, which recess overlaps the row of apertures 6, for about half their diameter. 90

The section 3, (Fig. 6) is provided with oppositely disposed ribs 15—16, having teeth 17—18, respectively integral therewith. As shown in dotted lines a cored out recess 19, is provided in one side of section 3, and overlaps the row of passages 7, and a cored out recess 20, is provided in the opposite side of said section and overlaps the row of apertures 9, for a suitable distance or approximately half their diameter. Between the apertures 9, the walls of the section are cored out to provide passages 21, which communicate with the passages 8, and open outwardly through one side of the section.

As shown in Fig. 7, the section 4, is pro-

vided with a rib 22, having teeth 23, integral therewith. Section 4 is also provided with a rectangular recess 24, which overlaps the row of apertures 10, to about 5 half their diameter. A plurality of passages 25, are provided in the wall of section 4, between the apertures 10, which passages connect with the apertures 11, outwardly and open through one side of the section.

10 All of the ribs and teeth on the different sections are offset so as to fit above and below each other to permit the respective side of the sections to abut one another when the broom is assembled.

15 The operation is as follows:

A suitable number of fiber bundles 26, are inserted in the apertures 5, 6, 7, 8, 9, 10 and 20 11, after which the sections are clamped together. When sections 2 and 3 are placed together the teeth 17, project through the passages 13, into the row of apertures 5. As shown in Fig. 4, rib 15 engages in the recess 14, of section 2, and rib 12 of section 2, engages in recess 19, in section 3, and both ribs 25 overlap the respective rows of apertures 6 and 7.

When section 4, is placed adjacent section 3, the teeth 23, engage in the passages 21, and the teeth 18, engage in the passages 25, and 30 project into the respective rows of apertures 8 and 11. Also rib 16, engages in recess 24, in section 4, and rib 22, engages in the rectangular recess 20, in section 3. The respective ribs 22 and 16, project into the respective rows of apertures 9 and 10.

When these sections 2, 3, and 4, are clamped together with the tufts of broom fiber in place the respective teeth and ribs interfitting in the recesses and passages 40 firmly bind and wedge the fiber tufts or bundles in position.

The main sections are clamped together by means of bolts 27, which extend through aligned apertures 28, in the end and middle 45 auxiliary sections.

As shown in the present case three auxiliary sections comprise one main quarter of the drum or one drum section and the outer sections 2 and 4, are beveled as at 29, 50 Fig. 4, to properly interfit with the other main drum sections. However, it is obvious that as many auxiliary sections as desired may form one main drum section.

The main drum sections are secured to 55 end plates 30, which are connected on a shaft 31, in any suitable manner.

Many details of construction may be varied and numerous changes may be made in the arrangement of the sections and binding elements without departing from the principles of this invention and I therefore do not desire to limit the patent when issued otherwise than necessitated by the prior art.

I claim as my invention:

65 1. A broom comprising sections having

apertures therein, broom fibers in said apertures, and means secured to each section for clamping and wedging the fiber in the apertures in the other sections.

2. A broom comprising drum sections 70 having apertures therein, broom fiber inserted in said apertures, and toothed means engaging in said apertures for wedging and binding the fiber in place when the sections are clamped together. 75

3. In a device of the class described, a broom comprising an apertured sectional drum, transverse passages and recesses in said drum sections, and members secured to the sections for engaging in the passages 80 and recesses and partly filling the apertures.

4. In a device of the class described, a drum constructed of sections each having apertures therein to receive broom fibers and ribs and teeth on each section for extending 85 into the apertures to bind the broom fibers therein.

5. A broom of the class described comprising a plurality of sections each having apertures therein, broom fiber inserted in 90 said apertures, and members integral with said sections engaging in said apertures for wedging and clamping the fiber in place.

6. A broom comprising a plurality of sections having apertures therein, broom fiber 95 in said apertures, said sections having recesses overlapping part of said apertures and passages opening from the other of said apertures, and members on the sections engaging in the recesses and passages to bind the broom fiber in place. 100

7. In a broom of the class described sections provided with radial apertures there-through and lateral passages communicating with said radial apertures, broom fiber inserted in the radial apertures, and means integral with the sections interfitting in the passages and apertures to bind the fiber in place. 105

8. In a device of the class described a plurality of sections having apertures therein, broom material inserted in said apertures, and ribs having teeth on the sections adapted when the sections are clamped together to firmly bind the broom material in 110 place and when unclamped to release the material. 115

9. In a broom of the class described, a plurality of interfitting apertured drum sections, and fiber tufts in said apertures held in position when said sections are secured together. 120

10. A broom of the class described comprising a plurality of apertured drum sections provided with teeth and ribs, and brush tufts held in position in said apertures by the teeth and ribs of one section engaging in the apertures of another section. 125

11. A broom comprising a plurality of passaged drum sections, ribs thereon, and 130

brush tufts held in the drum passages by said ribs.

12. A broom comprising a plurality of apertured drum sections, teeth thereon, and 5 fiber tufts wedged in said apertures by the teeth of one section engaging in the apertures of an adjacent section.

In testimony whereof I have hereunto subscribed my name in the presence of two subscribing witnesses.

PETER DRUGAS.
